UNITED STATES PATENT OFFICE.

WILLIAM G. O'BRIEN, OF AKRON, OHIO, ASSIGNOR TO THE GOODYEAR TIRE & RUBBER COMPANY, OF AKRON, OHIO, A CORPORATION OF OHIO.

MACHINE FOR MAKING FIBER COMPOSITION.

Application filed September 16, 1922. Serial No. 588,665.

My invention relates to a machine for making a fiber composition, and it has particular relation to machines of the character designated of the type known as the Fourdrinier machines, which are commonly used in the manufacture of paper.

One object of my invention is to provide a novel type of machine whereby the fiber composition is protected during the course 10 of its treatment from sudden strains and the possibility of displacement of the fibers while passing through a compressing process.

Another object of my invention consists 15 in providing very accurately regulated means whereby pressure may be applied gradually upon the fibrous composition, while passing through a compressing operation.

20 Another object of my invention is to provide a machine of the Fourdrinier type which is particularly adapted for the manufacture of thick fibrous material.

A still further object of my invention consists 25 in providing a novel arrangement of the machine elements which is particularly adapted for a continuous production of fibrous composition, in which a traveling screen or wire strains the fibers from a liquid 30 while passing up an inclined plane, and washes the same when rubber coated fibers are employed, while passing over an adjacent horizontal plane.

Heretofore it has been customary, in machines of the Fourdrinier type, to deposit 35 the fibers upon a moving screen or porous belt, which passes over a suction box adapted to remove therefrom the liquid in which the fibers were suspended. The screen therefore 40 after carries the fibers between two adjacently disposed pressure rolls, one of which is disposed beneath the travelling screen, and the other of which is disposed above the screen and engages the fibrous composition 45 deposited thereon.

An objection to the aforementioned type 50 of machine is that when a thick composition is passed between the pressure rolls, the fibers are sometimes broken, and are frequently displaced from their natural felted arrangement, owing to the sudden application of the relatively high pressure necessary to properly remove the liquid therefrom. This difficulty renders the commonly used

Fourdrinier machine unsuitable for making 55 thick materials, such as cardboard, which is now usually formed in layers as a result. Another disadvantage of the machine in question is that the suction boxes may only be applied to the bottom side of the 60 fibrous composition, since, if applied to the top side, a portion of the fibers would be carried directly into the suction box along with the liquid removed thereby.

By my invention I have eliminated the 65 aforementioned objections by the use of a second or auxiliary screen which engages the top of the fibrous composition and is instrumental in causing the pressure necessary 70 for the proper compression of the material to be applied gradually, thus preventing the breakage and displacement of the fibers thereof. Also, in a machine constructed in accordance with my invention, suction boxes may be used on top of the deposited fiber 75 composition as well as below, because the upper screen prevents the passage of any of the fibers therethrough, but permits of the passage of liquids. As the auxiliary 80 screen moves with the fiber carrying screen, it serves to protect the material from any injury to, or displacement of, the fibers, or strain thereon.

In the accompanying drawings, Fig. 1 is 85 a side elevational view of a machine constructed in accordance with my invention, the side frame members being omitted for the sake of clearness; and Fig. 2 is a similar view of a machine constructed in accordance 90 with another form which my invention may assume.

In the drawings, I show a fiber composition making machine comprising a traveling screen or carrier belt 3, a portion of which passes through a lowermost horizontal plane 4, over an idler pulley 5, up an inclined plane 6, over an idling pulley 7, through an uppermost horizontal plane 8, over a driving pulley 9, and back to the horizontal plane 4. While passing up the inclined plane 100 6, a quantity of liquid, having fibers suspended therein, flows through the screen, being introduced thereto through a conduit 10, and the fibrous suspended therein are strained therefrom by the screen 3. The 105 fibers are deposited upon the screen while it passes up the horizontal plane 6, a large portion of the liquid being removed there-

from by means of a suction box 11, disposed adjacent to the inclined plane 6 in engagement with the bottom of the screen 3.

The fibers and the liquid from the conduit 10 are prevented from escaping over the sides of the screen on the inclined plane 6, by means of deckle straps 12, one of which is disposed at each side of the screen and removes therewith until a considerable portion 10 of the liquid has been removed from the fibers, after which they will remain in substantially their original form without further assistance from the deckle straps. The straps 12 are moved in the inclined plane 15 6 by the wire 3 and pass over a lower idling pulley 13, adjacent to the pulley 5 and an upper pulley 14, adjacent to the pulley 7.

The fibers deposited upon the screen 3, while on the inclined plane 6, are carried 20 into the horizontal plane 8. The top surface of the fibers is engaged by means of an auxiliary screen or wire 15, while on the screen 3 in the horizontal plane 8. The auxiliary screen 15 passes over a front idling 25 pulley 16 and a rear idling pulley 17. The screen 15 may be driven, either from the screen 3 or it may be separately driven, in which event it is necessary that means be provided for driving the two screens at exactly the same speed, as a difference of speed 30 would ruin the matted formation of the fibers, and probably crush and break a large number thereof.

The pulley 16 is disposed at such distance 35 from the horizontal plane 8 of the screen 3 that the screen 15 initially engages the fibrous composition without exerting any strain thereon. The fibrous composition, illustrated at 18, passes between the wires 40 3 and 15, and, while in that position, is subjected to treatment by a suction box 19 disposed below the wire 8. If any further treatment of the fibers is desirable, as for example, when rubber coated fibers are employed, the composition is next treated by 45 being washed with a liquid rubber precipitant, sprayed thereon by means of a device 21 disposed above the screen 15 and cooperating with a suction box 22, below and in 50 engagement with the carrier screen 3. The purpose of the treatment with the precipitating fluid is to displace, as far as possible, any rubber solvent or other undesirable liquid which may be contained in the fibrous 55 mixture. The suction box 22 serves to remove any liquid which comes through the fibers from the spray 21, or which is displaced by the liquid from the spray 21.

The auxiliary belt 15 is engaged by an adjustable pressure roll 23, disposed substantially opposite to a cooperating pressure roll 24, in engagement with the screen 3. Both of the rolls 23 and 24 are disposed at some distance from the front pulley 16 of 60 the screen 15, and the tension on the screens

or wires 15 and 3 at 8 is such that the pressure is exerted upon the material carried by the screen 3 very gradually, starting at the time that the material passes beneath the pulley 16, and ending as it passes between 10 the rollers 23 and 24 at which time the fibers have been compressed to the desired degree. The roller 23 is adjustable with respect to the roller 24 in order that the pressure exerted thereby may be controlled as 15 desired. The entire auxiliary belt supporting mechanism is also adjustable with respect to the carrying belt supporting mechanism, in order that different thicknesses of material may be accommodated thereby. 20

From the foregoing description it will be apparent that I have provided a machine in which the fibrous material is protected from injury of any type and in which the pressure exerted thereon, for the purpose of compressing the same, is exerted very gradually, thus avoiding any possibility of injury to the individual fibers, and the possibility of disturbing the matted relation thereof. Also, it will be apparent that this invention, used on a Fourdrinier machine, enables the operator to make a fibrous sheet material, such, for example as cardboard, of any desired thickness. 25

Also, it will be apparent that I have increased the efficiency of the liquid removing means by disposing suction boxes on both sides of the material, which is possible since both sides are protected by means of a screen. In addition the spraying device 21 100 may throw a liquid thereon with considerably greater force or in greater volume than on a material supported upon a single screen, since the fibers cannot be disarranged thereby owing to the fact that they are held 105 in position between two screens.

It will also be apparent that I have provided a novel arrangement of parts in which the fibrous composition is picked up by a traveling screen while passing up an 110 inclined portion of its path, and in which the fibers are compressed and washed while passing over an adjacent horizontal plane, which arrangement tends to simplify the 115 construction of the machine.

In another form of my invention, as best illustrated in Fig. 2, I provide another novel type of pressure exerting mechanism. In this device the carrier belt 3 passes through a horizontal plane 8, through which it carries the fibrous material in the directions indicated by the arrows 4^a. While passing through the plane 8, the material is engaged by an auxiliary belt 15, which moves in the directions indicated by arrows 15^a, and is washed by means of a spraying mechanism 21 and a cooperating suction box 22, as described in connection with the machine illustrated in Fig. 1. The pressure applying mechanism consists of a plurality of spheres 120 125 130

23 which are divided into a front compartment 24 and a rear compartment 25. The spheres in the front compartment 24 are smaller and lighter in weight than are those 5 in compartment 25, so as to apply a gradually increasing pressure on the fibrous material as it passes through the machine. A relatively long suction box 26 is disposed opposite to the pressure applying device, so 10 as to remove any liquid which may be forced from the fibrous composition thereby. The pressure applying device may consist of any desired number of compartments, depending on the material to be manufactured. The pressure exerted by the device 15 may be regulated by removing or adding to any of the compartments any desired number of the spheres. Barriers 27 prevent the movement of the spheres 23 with the belt 15 20 over which they roll as the belt moves.

Although I have illustrated several forms of my invention and have described in detail several applications thereof, it will be apparent to those skilled in the art that it is 25 not so limited but that various minor changes and modifications may be made therein without departing from the spirit of my invention, and I desire to be limited only by the scope of the appended claims.

30 What I claim is:

1. A machine for making fiber composition comprising a movable screen adapted to transport the fibers, an auxiliary screen disposed in engagement with the fibers and 35 adapted to move therewith and means for applying pressure on said auxiliary screen comprising a plurality of weight members of circular cross section disposed upon said auxiliary screen.

40 2. A machine for making fiber composition comprising a movable screen adapted to transport the fibers, an auxiliary screen disposed in engagement with the fibers and adapted to move therewith, and means for 45 applying pressure on said auxiliary screen comprising a plurality of members of graduated weights disposed upon said auxiliary screen.

3. A machine for making fiber composition 50 comprising a movable screen adapted to transport the fibers, an auxiliary screen disposed in engagement with the fibers and adapted to move therewith, and means for applying pressure on said auxiliary screen comprising a plurality of groups of members 55 disposed upon said auxiliary screen and adapted to exert a graduated pressure thereon.

4. A machine for making fiber composition 60 comprising a movable screen adapted to transport the fibers, an auxiliary screen disposed in engagement with the fibers and adapted to move therewith, and means for applying pressure on said auxiliary screen comprising a plurality of separate rotatable

spherical weight members disposed upon said auxiliary screen.

5. A machine for making fiber composition comprising a movable screen adapted to transport the fibers, an auxiliary screen disposed in engagement with the fibers and adapted to move therewith, and means for applying pressure on said auxiliary screen comprising a plurality of spherical weight members disposed upon said auxiliary 75 screen.

6. A machine for making fiber composition comprising a movable screen adapted to transport the fibers, an auxiliary screen disposed in engagement with the fibers and adapted to move therewith, and means for applying pressure on said auxiliary screen comprising a plurality of weight members of circular cross section disposed upon said auxiliary screen, and means for retaining 80 said members on a predetermined portion of said screen.

7. A machine for making fiber composition comprising a movable screen adapted to transport the fibers, an auxiliary screen disposed in engagement with the fibers and adapted to move therewith, and means for applying pressure on said auxiliary screen comprising a plurality of spherical weight members disposed upon said auxiliary screen, and means for preventing movement of the weight members with the screen. 85

8. A machine for making fiber composition comprising a movable screen adapted to transport the fibers, an auxiliary screen disposed in engagement with the fibers, and adapted to move therewith, and means for applying pressure on said auxiliary screen comprising a plurality of graduated weights disposed upon said auxiliary screen. 100

9. A machine for making fiber composition comprising a movable screen adapted to transport the fibers, an auxiliary screen disposed in engagement with the fibers and adapted to move therewith, and means for applying pressure on said auxiliary screen comprising a plurality of spherical members of relatively different weights disposed upon said screen. 110

10. A machine for making fiber composition comprising a movable screen adapted to transport the fibers, an auxiliary screen disposed in engagement with the fibers, and adapted to move therewith, and means for applying pressure on said auxiliary screen comprising a plurality of members of relatively light weight and a plurality of relatively heavier weight disposed upon the auxiliary screen, the weight members being so arranged that the composition is first compressed by the relatively light weight members and subsequently by the heavier weight members. 120

11. A machine for making fiber composition comprising a movable screen adapted to 125

1 transport the fibers, an auxiliary screen disposed in engagement with the fibers, and 15
5 disposed in engagement with the fibers and adapted to move therewith, and means for applying pressure on said auxiliary screen comprising a plurality of spherical members of relatively different weights disposed upon the auxiliary screen, the weight members being so arranged as to compress the composition gradually.

10 12. A machine for making fiber composition comprising a movable screen adapted to transport the fibers, an auxiliary screen dis-

posed in engagement with the fibers, and adapted to move therewith and means for applying pressure on said auxiliary screen 15 comprising a plurality of spherical members of relatively different weights disposed upon the auxiliary screen, the weight members being so arranged that the fiber composition is gradually compressed during its course of 20 travel by successively heavier weights.

In witness whereof, I have hereunto signed my name.

WILLIAM G. O'BRIEN.
